Primary Examiner—Janice E. Seeger*Assistant Examiner*—Mary Ann Calabrese*(74) Attorney, Agent, or Firm*—Price, Heneveld, Cooper, DeWitt & Litton, LLP**CLAIM**

I claim the ornamental design for a hanging basket collar, as shown and described.

DESCRIPTION

FIG. 1 is a perspective view of a hanging basket collar of my invention;

FIG. 2 is a front elevational view of the hanging basket collar shown in FIG. 1;

FIG. 3 is a right side elevational view of the hanging basket collar shown in FIG. 1;

FIG. 4 is a left side elevational view of the hanging basket collar shown in FIG. 1;

FIG. 5 is a top plan view of the hanging basket collar shown in FIG. 1; and,

FIG. 6 is a bottom plan view of the hanging basket collar shown in FIG. 1.

In the drawings, the broken lines represent environmental structure forming no part of the claim.
